DESIGN FOR A COMBINED ELECTRIC FAN AND HEATER

Lee B. Green, Lakewood, Ohio

Application December 23, 1943, Serial No. 112,080

Term of patent 14 years

(Cl. D81—10)

To all whom it may concern:

Be it known that I, Lee B. Green, a citizen of the United States, residing at Lakewood, in the county of Cuyahoga and State of Ohio, have invented a new, original, and ornamental Design for COMBINED ELECTRIC FAN AND HEATER, of which the following is a specification, reference being had to the accompanying drawing, forming a part thereof, in which:

Fig. 1 is an outside elevational view of a com-

bined electric fan and heater embodying my new design;

Fig. 2 is a front elevational view of the device; and

Fig. 3 is a rear elevational view thereof.

I claim:

The ornamental design for a combined electric fan and heater, substantially as shown.

LEE B. GREEN.
